UNITED STATES PATENT OFFICE.

MARTIN W. BRUESHABER, OF CHICAGO, ILLINOIS, ASSIGNOR TO GOSS PRINTING PRESS COMPANY, A CORPORATION OF ILLINOIS.

MACHINE FOR CASTING STEREOTYPE PLATES.

Application filed March 21, 1921. Serial No. 454,001.

To all whom it may concern:

Be it known that I, MARTIN W. BRUESHABER, a citizen of the United States, residing at Chicago, in the county of Cook and State of Illinois, have made certain new and useful Improvements in Machines for Casting Stereotype Plates, of which the following is a specification.

The invention relates to machines for casting stereotype printing plates and more particularly to mechanism operating automatically to strip the plate and matrix apart and to lift the plate free from the drag so that it may be readily removed therefrom for trimming or other subsequent operations.

Objects and advantages of the invention will be set forth in part hereinafter and in part will be obvious herefrom, or may be learned by practice with the invention; the same being realized and attained by means of instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a side elevation showing a machine embodying the invention in the plate casting position;

Fig. 2 is a side elevation showing the machine of Fig. 1 in plate delivering position;

Fig. 3 is a vertical longitudinal section on an enlarged scale, taken substantially through the center of the drag and associated mechanism of Fig. 2;

Fig. 4 is an enlarged fragmentary detail view, on the line 4-4 of Fig. 2, looking in the direction of the arrows;

Fig. 5 is a transverse vertical section likewise on an enlarged scale taken on line 5-5 of Fig. 2, showing the plate disengaged from the matrix, and showing a form of removing device ready to take the plate;

Fig. 6 is a horizontal section, on an enlarged scale, on the line 6-6 of Fig. 1, looking in the direction of the arrows, and

showing a cast plate within the casting chamber;

Fig. 7 is a greatly enlarged fragmentary section taken on line 7-7 of Fig. 3;

Fig. 8 is a vertical central section on line 8-8 of Fig. 6, more or less diagrammatic in character, showing the form of the casting chamber;

Fig. 9 is a side elevation, with the drag or concave casting member in longitudinal section, showing a different form of mechanism for operating the plate raising saddles;

Fig. 10 is a full end elevation of the drag or concave casting member, looking at Fig. 9 from the right;

Fig. 11 is a fragmentary horizontal section on line 11-11 of Fig. 9;

Fig. 12 is a side elevation, with parts in section of a different form of mechanism for operating the plate raising saddles;

Fig. 13 is an elevation taken on line 13-13 of Fig. 12;

Fig. 14 is a horizontal sectional view, taken on the line 14-14 of Fig. 12; and

Fig. 15 is a fragmentary detail showing a manual control for the unitary end ring and saddle mechanism.

The present invention is directed to making a simple stereotype plate casting machine, very much along standard lines so far as concerns its general features, while adding thereto, or introducing therewith, novel features and instrumentalities operating or conducting to render the machine largely automatic or approximately so; to facilitate the discharge and the handling of the hot plate preparatory to finishing; to quickly and easily strip the cast plate from the matrix and to separate or space it from the wall of the drag preparatory to its removal from the casting machine, either manually or by a machine, and to effectuate the foregoing by simple, sturdy and reliable mechanism, operating automatically in the ordinary operation, or by the usual movements, of the parts of the casting machine. Other features and objects than those enumerated will be set forth in connection with the detailed description of the machine.

In the embodied form, devices are provided engaging with each end, preferably each arcuate end, of the cast plate to lift the plate clear from the matrix and the wall

of the drag. Preferably in connection therewith, as embodied, a plate is cast having a tail at either end, or a tail at the bottom and a riser at the top, the plate lifting devices engaging with the two tails, and lifting the plate clear of the matrix and the drag wall, and thereby positioning the plate so that it may be removed either manually or by mechanism without danger of injury to the matrix or to the plate.

As embodied further, the plate lifting members are nested in the wall of the drag during the casting operation and are projected from their nests or seats to lift the plate as described. The plate lifting members are preferably two arcuate saddles nested in recesses in the drag wall and, when projected, engaging the tails at either end of the plate to strip it from the matrix and lift it free from the drag. The saddles are preferably spring pressed into their nests and are automatically moved therefrom to lift the plate from the matrix and the drag wall.

Referring to the embodiment of the invention illustrated by way of example in the accompanying drawings, a casting machine is shown having a vertical stationary core and a traveling drag, the plate being carried away from casting position in the drag, the drag traveling preferably to a horizontal position for the delivery or removal of the plate.

Means are provided by the invention for stripping the plate from the matrix, and for removing and positioning the plate for ready removal from the drag, either manually or by the operation of the mechanism. In connection with the embodied form of such means, they operate automatically through the travel of the drag, and preferably upon the plate and drag arriving at delivery position. Furthermore, the machine is preferably capacitated to cast a plate having a tail or projection at each curved end thereof, the automatic plate removing means engaging these tail or projecting portions of the plate in the removing action. Other features and details of the invention will be pointed out at later points in connection with the detailed description of the invention.

In said embodied form, as herein illustrated in an exemplary manner, the convex or core 1 is vertically arranged or positioned, and is preferably fixed in position upon the base 2 of the machine. The core may be provided with cooling devices and the like, of any suitable or approved form, but they are not shown in the drawing as they constitute no direct part of the present invention.

In the embodied form, the concave or drag 3 travels to and fro between a vertical position in cooperation with the core 1 for cast-

ing the plate, and a horizontal position for the delivery of the plate, the former position being shown in Fig. 1 and the latter position in Fig. 2 of the drawings. The drag may be provided with cooling devices, 70 if desired.

Means are provided for locking the core and drag together during the casting operation, and the illustrated form thereof comprises a pair of pins or lugs 4 at one end, 75 and upon the opposite sides, of the drag and a pair of pins 5 located at the other end of, and upon opposite sides of, the drag. Cooperating with the pair of lugs 4, respectively, are a pair of hooks 6, fixed on a shaft 7, which shaft is positioned transversely to the core and is mounted at the back thereof in bearings upon the machine structure. Cooperating with the pair of pins 5, respectively, are a pair of hooks 8, 80 which are fixed on a shaft 9, this shaft being likewise located transversely and at the back of the core 1 and being journaled in suitable bearings. Means are provided for causing the two pairs of hooks to move concurrently or simultaneously, and as embodied, an arm 10 is fixed to shaft 7, and an arm 11 is fixed to shaft 9, these two arms being connected together by a link 12. A hand lever 13 is shown for actuating the 85 mechanism just described. So far as concerns the principal features of the present invention, such fastening means may be of any suitable or approved form, and the illustrated mechanism is the same as that 90 shown and described in the copending application of Albert A. Henzi, Ser. No. 408,203, filed Sept. 4, 1920, copending here-with.

Means are provided for traveling and 105 guiding the drag to and fro between the plate casting and plate discharging positions, and such means may be of any suitable form so far as concerns certain features of the invention. As embodied, a pair 110 of lugs 16 and 17 project from the back or exterior of the drag 3, and loosely carried in internal apertures in these lugs is a shaft 18, the shaft having retaining collars 19 and 20 at the ends thereof. Shaft 115 18 is likewise loosely mounted in a pair of arms 21 and 22 at one end of the arms, and at their opposite ends these arms 21 and 22 are fixed to a shaft 24, by 120 suitable means such as pins 25 and 26. The shaft 24 is mounted to rock or partially rotate to and fro in bearings 27 and 28, formed in the machine frame 29. Suitable means are provided for so rocking or partially rotating to and fro the shaft 24, which means 125 may be operated manually or by a machine, and as shown herein a hand lever 30 is fixed to one end of the shaft 24 for this purpose.

Also constituting a part of the means for 130 traveling the drag to and fro, there is pro-

vided in the present embodiment, cooperating with the foregoing mechanism, a pair of pintles 35, which project from the drag 3 at the opposite sides thereof. Mounted 5 on the respective pintles are a pair of rollers 36, these rollers running on a pair of trackways 37 formed on the opposite sides of the machine frame.

In connection with these, means are provided 10 for locking the drag in the plate-discharging position, and as embodied, a pair of hooks 38 are pivotally mounted, respectively, on the opposite sides of the machine frame, upon corresponding pivot pins 39.

15 The hooks 38 are provided at their forward ends with bevel faces 40, and at their opposite ends with tails 41. The operation of these locking devices will be clear from Figs. 1 and 2. The projecting ends of the

20 pintles of rollers 35, as the drag rocks from the plate-casting position of Fig. 1 to the plate-discharging position of Fig. 2, engage with the bevel faces 40 of the hooks, and the hooks thereupon swivel on their pivots to

25 receive the pintles 35 and to thereby lock the drag in the position of Fig. 2. By rocking the hooks by means of their tails 41, they will be unlocked or disengaged from the pintles preparatory to the return travel

30 of the drag to the plate-casting position of Fig. 1. These devices so far as concerns many features of the invention will be of any approved or suitable form, but as shown herein they are similar to those shown and

35 described in said copending application Ser. No. 408,203, of Albert A. Henzi.

Referring now to the construction of the automatic plate-removing means, and to certain of the cooperating parts, there are provided 40 suitable end stops 46 and 47, to protect the ends of the matrix 45 from the hot poured stereotype metal and to form wholly or in part the curved beveled ends of the plate. Suitable devices may be provided 45 for holding the straight edges of the matrix in position within the box or drag 3, and these may be of any suitable or adequate form, the same not being shown herein.

In the embodied form, and according to 50 one feature of the invention, the casting chamber is shaped to cast a plate 48 with an intermediate printing portion 49 (which is the plate proper, that is, it carries the operating surface of the finished plate which goes upon the form cylinder of the press), with the usual riser 50 at one curved end, and with a tail 51 at the opposite curved end of the plate from the riser. The embodied 55 form of plate removing mechanism cooperates with these two tails 50 and 51 at the opposite curved ends of the plate, and said mechanism preferably does not engage with the plate proper 49.

The embodied form of plate removing 60 means lifts the plate bodily from the matrix

and drag, and brings it to rest as shown in Figs. 3 and 5, preparatory to the removal of the plate, either by mechanism or by hand. The two mechanisms so operating may be of the same or similar construction and will be 70 described together. As embodied two articulate yokes 56, one at either end of the plate, and of like curvature and size or radius with the exterior of the stereotype plate 48 are nested or seated within a recess 57, formed 75 either in the wall proper of the drag or in a recess in the head stop 47 and tail stop 46, as may be found most convenient or advisable, so that when in the casting position, shown in Fig. 6, the outer surface of the 80 yoke presents an unbroken surface with the inner surface of the drag 3.

Means are provided for projecting the yokes 56 from the nests or recesses 57 at the plate-discharging position, to bring the cast 85 plate to a position such as is shown in Figs. 3 and 5. In the embodied form of such means, there is fixed to each of the yokes 56 a stem 58, projecting backwardly through an aperture in the back wall of the drag, and preferably located centrally with respect to the curved shape or dimension of the drag. Within this aperture is a bushing or sleeve 59, provided at its inner end with a shoulder 60. Coiled about stem 58, and in compression between the shoulder 60 of bushing 59 and a collar 61 fixed upon the outer end of stem 58, is a spring 62. In the outer end of each of the stems 58 there is preferably a friction wheel 63. Keys or splines 64 are provided to prevent rotation of the stems 58 when the saddles are projected, that is are out of their seats 57.

The springs 62 operate to press the corresponding yokes or saddles 56 into their seats in the wall of the drag, as shown in Fig. 6. Means are provided operating automatically as the casting box comes to the plate-discharging position of Fig. 2, to engage with the stems 58, and to move them against the springs 62 to the position of Fig. 5 to bring the plate to discharging position.

In the embodied form of actuating means for the saddles, the right-hand stem 58, or its roller 63, in Figs. 2 and 3, as the drag comes to the plate discharging position, engages with an arm 68, fixed on a shaft 69, which shaft is mounted in fixed or non-rotating position in the machine frame. As embodied, the corresponding mechanism, operating upon the stem 58 or its roller 69 at the left hand end of Figs. 1 and 3, comprises a lever 70, fixed on a shaft 71, which is journaled at 72 and 73 in the machine frame. Collars 74 and 75 serve to keep the shaft 71 longitudinally in position. At one of its ends lever 70 is provided with a friction roller 76, adapted to engage with a lug 77 when the drag comes to the plate-discharging position. Lever 70 is thus rocked 130

such a distance that its opposite end engaging with roller 63 will impart to its saddle movement equal to that of the other saddle 56, so that the plate 48 will be moved or lifted throughout its length an equal distance from the drag 3 and from the matrix 45.

In Fig. 6 one of the saddles 56 is shown nested in the drag wall during the casting 10 operation. In Fig. 8 the form of the casting chamber for casting a tail at each end of the plate is shown.

In Fig. 5 part of a mechanical, automatically operating plate remover 80 is 15 shown, cooperating with the plate as positioned for discharge by the mechanism hereinbefore described. This device, shown by way of example, is the carrier illustrated and described in copending application. 20 Ser. No. 407, 987, filed September 3, 1920, of Albert A. Henzi.

The carrier 80 rotates in the direction of the arrow in Fig. 5, and the edge 81 thereof engages with the edge of plate 48, carrying 25 the plate around to a position on top of the carrier 80, and it is then removed for delivery or to the machine of which the carrier 80 forms a part in said copending application.

30 In Figs. 1, 2, 3, 5, 6 and 8 the casting box is shown with a solid back, while in Fig. 12 is shown a two part drag, that is, a drag having a receding back portion movable to and away from the matrix sheet, the same 35 or similar to that shown in copending application of Albert A. Henzi, Ser. No. 408,203. In Figs. 3, 5, 6, 8, 12 and 13, the plate lifting saddles and the end rings for the matrix sheet are shown separate from each other and movable relatively to each other, while in Figs. 9 and 40 10, the end rings for the matrix sheet and the saddles or plate lifting devices are shown unitary or integral.

45 In actual practice, however, it will usually be found convenient or advisable to use the combined or unitary end rings and plate lifters when the solid back drag is employed, using therewith the spring-acting or automatically operating matrix stripping jaws or side gages. When the drag with the receding back is employed, usually automatically operating, the separate end rings and saddles or plate lifting devices can be 50 used, or the unitary end rings and lifting devices may be utilized, as desired. Other changes or arrangements can be made, but the foregoing are the present preferred arrangements of the mechanism for practical 55 commercial work.

In particular cases, different arrangements of the mechanism may be utilized as may be found most advantageous. It will be understood for instance that the receding back shown in Fig. 12 may be used with 60

the form of saddles and the form of actuating means therefor shown in Figs. 1 to 8, or the combined or unitary end rings and lifting saddles shown in Figs. 9 and 10 may be employed with the other mechanisms shown in the other figures of the drawings. The various applications are not shown and described in added detail to avoid undue extension of the drawings and description but will be clear to anyone skilled in the art. 75

In Fig. 9 of the drawings, the end rings (which are arcuate in form and protect the ends of the matrix sheet 45 from the molten metal) and the plate lifting devices or saddles are of unitary construction, and when this structure is lifted or moved outwardly to deliver the cast plate 49 or to bring the plate to delivery position, the end rings are thereby also moved away from the matrix sheet 45, which is then free to be flexed and stripped from the cast plate. These unitary end rings and saddles will operate with either a solid back drag or a drag with the part behind the matrix sheet 80 recessible or movable backwardly from the matrix sheet when in casting position, although the unitary ring and saddle and the recessible back will not usually be employed together.

90 Referring in detail to the said structure, the unitary ring and saddle construction 90 is shown mounted in the drag 3 at each end of the matrix sheet 45, being shown partly in cross-section and partly in side elevation in Fig. 9, and in end elevation in Fig. 10. The body 91 is reciprocable inwardly and outwardly and when retracted is nested in a correspondingly shaped recess 92 in the drag. Each of the devices is provided with a lip or flange 93 which extends over the corresponding curve edge of the matrix 45, 95 performing the function of the end ring.

100 A form of means for automatically lifting or delivering the cast plate 48 is shown in this figure different from the corresponding means in the other figures, although it will be understood so far as concerns many features of the invention that this form of actuating mechanism may be employed with the other forms of end rings and plate lifting devices, or the other forms of actuating means may be used with the unitary end ring and saddle. The actuating means shown in Figs. 9, 10 and 11 are adapted to be used with the form of drag-operating means shown in Figs. 1 and 8, or with the automatic means for actuating the receding back such as is shown in co-pending application, Ser. No. 408,203, of Albert A. 105 Henzi.

110 In this form of actuating mechanism shown in Fig. 9 to 11, stems 95 are fixed centrally to and projecting backwardly from the unitary rings and saddles 90 and are located centrally thereof and of the drag. 115 120 125 130

These stems are reciprocable in apertures in the back of the drag 3. The reciprocable stems 95 have their outer ends fixed to a frame 96 in a suitable manner, and are shown 5 shouldered against one side of the frame, with reduced portions 97 passing through apertures in the frame and with nuts 98 screw-threaded on the ends thereof. The frame 96 has a rectangular yoke 99 fixed 10 thereto and extending downwardly therefrom, the yoke being fixed to the frame by suitable means, such as screw bolts 100. A journal box 101 is mounted within the yoke 99 so as to be reciprocable therewithin upon 15 guides formed between the journal box and the yoke 99 and frame piece 96. Journaled within the journal box 101, and rotatably mounted on shaft 18, is an eccentric 102, which is fixed to an arm 103, extending 20 outwardly from the eccentric. Pivoted at 104 to the end of the arm 103 is a rod 105, the other end of which is pivotally mounted on a cross rod 106 mounted on the machine frame. The eccentric 102, arm 103 and rod 25 105 are similar to those employed for automatically operating the receding back portion of the drag as the drag is swung to and fro between casting and delivery position, as shown and described in said application S. 30 N. 408,203, of Albert A. Henzi. In Figs. 9 and 10, 88 is the handle for opening the matrix clamping jaws and 89 is the handle for rocking the jaws by hand to stripping position, the complete mechanism being 35 shown in said Henzi case.

The manner of operation of the mechanism just described is substantially as follows:—

The drag is rocked to and fro between casting position and delivery position by means of shaft 24, arms 21 and 22 and shaft 18, as already described in connection with Figs. 1 to 8. As the drag 3 stands at casting position with the cast plate therewithin, the members 90 are within the corresponding recesses 92, and the flanges 93 are pressed closely against the curved edges of the stereotype plate. As the drag rocks downwardly from casting position to the position of Fig. 40 9 on arms 21 and 22, the eccentric 102 has rotary movement about shaft 18, due to its connection to the arm 103 and link 105, and the connecting parts. Frame 96 and yoke 99 are thereby moved toward the body of the drag, and the unitary rings and saddles 45 90 are lifted or moved outwardly from the recesses 92 to the position shown in Fig. 9. The journal box 101 has moved longitudinally within the yoke 99 to allow for the 50 movement of the shaft 18 with the arms 21 and 22. The matrix clips, which hold the straight edges of the matrix 45, may be of such form that the matrix sheet 45 will be stripped from the plate 49 during this movement, and for this purpose they may be of

the general form and manner of operation shown and described in said copending application S. N. 408,203, of A. A. Henzi.

Means are provided, in accordance with one feature of the invention whereby the end rings 90 may be lifted and lowered either automatically or at the option of the workman or may be lifted and lowered both automatically or by the workman. Fig. 15 shows the mechanism shown at the central 70 bottom part of Fig. 9, with additions for effecting the functions just described and constituting the present preferred form of the above-mentioned means.

In Fig. 15 rod 105 is pivoted at 170 to an 80 arm 171 which is fixed on a shaft 172. Fixed also on shaft 172 is a hand lever 173, provided with a latch mechanism 174. A sector 175 is mounted on the machine frame, and has notches 176 formed therein with which 85 the latch 174 engages. When arm 171 is in the full-line position of Fig. 15 the end rings 90 and associated parts will be in the position of Fig. 9, but when arm 171 is moved to the broken line position of Fig. 15, 90 it will rotate eccentric 102 and the end rings 90 will be drawn downwardly and be seated in the recesses 92. Thus the workman can raise and lower the end rings at will in changing or fitting the matrix without interfering with the automatically operating 95 actuating means.

In Figs. 12 to 14 of the drawings a present preferred form of means is provided 100 operable by the workman for actuating the saddles or plate lifting members. In this embodiment, said means is shown cooperating with the recessible back in the drag behind the matrix sheet 45, and the end rings for the curved ends of the matrix are separate 105 from the saddles or plate lifting devices. It will be understood without further amplification of the drawings, that this workman-operated mechanism could be applied to the unitary form of end rings and saddles 110 shown in Figs. 9 to 11, if desired, and with a solid back drag.

Referring now in detail to said embodiment shown in Figs. 12 to 14, saddles 110 of arcuate form are located near each end of 115 the drag 3, and are nested in recesses 111 in the end rings 109. The saddles 110 are fixed upon rods 112, respectively, which rods work in apertures transversely centrally located in the body of the drag 3. The saddles 110 are resiliently held in their seats in the respective recesses 111 by suitable means, and as shown coiled springs 113 encircle the rods 112, within enlarged apertures in the drag 3, the springs being in compression between the bottoms of the apertures and collars 114, fixed on the rods 112. At their exterior ends the rods 112 are provided with rollers 115.

Mounted on the machine frame, in coop- 130

erative position with respect to the two rods 112, respectively, are rods 116, mounted for longitudinal reciprocation in corresponding guiding brackets or lugs 117 mounted on the machine frame.

The left hand rod 116 in Fig. 12 has its bottom end pivotally connected at 118 to an arm 119, which arm is fixed on a shaft 120, journaled in the machine frame. Fixed on shaft 120 is an arm 121, pivotally connected at its outer end 122 to a connecting link 123, and the other end 124 of link 123 is connected to an arm 125, which is fixed to a shaft 126, journaled in the machine frame. Fixed to shaft 126 is an arm 127, which is pivotally connected at 128 to the bottom end of the other rod 116.

Fixed also to the shaft 126 is a pedal lever 130, and a spring 131 in tension between the machine frame and a pin 132, fixed in rod 116, tends to bring the mechanism to the position of Fig. 12. Fixed to lever 130 is a segment 133 having therein a notch 134. A pedal lever 135 is pivotally supported at 136 on the machine frame, and at its opposite end 137 is pivotally connected to a rod 138 reciprocable in an apertured lug 139 on the machine frame. A coiled spring 140 is mounted on the rod 138, in tension between lug 139 and a collar 141, fixed on the rod 138. A detent tooth 142 is formed on the upper part of the lever 135.

The manner of operation of the mechanism just described is substantially as follows:—

The rods 116 and the pedals 130 and 135 may be regarded as in the position corresponding to Fig. 8, when the drag 3 is at casting position. As the drag rocks downwardly to the position of Fig. 12, the rollers 115 engage against the tops of the corresponding rods 116, and as these are locked in position by the engagement of tooth 142 with notch 134, the saddles 110 are lifted to the position of Fig. 12, lifting the plate 49 clear of the matrix. The automatically operating matrix stripping devices will clear the matrix sheet 45 from the cast plate 49. These devices may be of any suitable form, such as the automatically operating clamps of the Henzi application already referred to.

After the plate 49 is removed, the workman can step on lever 135, whereupon notch 134 will be released from tooth 142, and springs 113 will force the saddles 110 back into their seats 111, at the same time rocking lever 130 in clockwise direction and moving notch 134 away from tooth 142. The saddles 110 are thus out of the way in changing matrix sheets. When the drag 3 is again swung upwardly to casting position, the rollers 115 will move away from the rods 116, spring 131 will lift the rods 116, and will thereby swing lever 130 until tooth 142

again engages in notch 134, thereby locking the rods 116 in position to operate in the manner already described when the drag 3 again swings downwardly to plate delivering position. The foot pedal 130 may be employed to restore the mechanism to the position of Fig. 12, should this be desired when the weight of the plate is on the mechanism or at any time after the release lever 135 has been operated.

Means are provided by the invention for manually operating the recessible back 150 of the drag 3. This recessible back is employed partly to effect clearance and stripping of the matrix from the cast plate while the plate is still lying in position within the drag, and the recessible back may have the construction and manner of operation of the similar mechanism shown and described in said application S. N. 408,203 of Albert A. Henzi, co-pending herewith including the automatically operating means for moving the back to and fro.

By the present invention means are provided for additionally moving the back manually, so that the back may be moved up, that is, inwardly to casting position, when the matrix sheet is changed, to determine whether or not there is a true and smooth fit of the new matrix sheet as held by the side gages or stripping clamps and by the end rings when these are in casting position. As herein embodied the mechanism of the recessible back may be the same as in said copending Henzi application Ser. No. 408,203, and the mounting of the back in the drag need not be described in detail.

The arm 150 is pivotally mounted at 153 in lugs 151, fixed to the recessible back, the arm being journaled on an eccentric 152 mounted on shaft 18. The arm 154 is fixed to eccentric 152, and its outer end is pivotally connected at 155 to a rod 156. This mechanism so far as described is substantially the same as that in the Henzi application referred to.

The other end of rod 156 is not pivoted to a fixed point on the frame, but is pivoted at 158 to an arm 159, which arm is fixed on a shaft 160, journaled in the machine frame. Fixed on shaft 160 is a hand lever 161, having a spring latch mechanism 162, which has a latch 163 adapted to engage with a toothed sector 164, mounted on the machine frame.

When latch lever 161 is left in locked position, the mechanism will operate the recessible back automatically as the drag 3 moves to and fro between plate casting and plate delivery positions, as the bearing 158 furnishes a fixed bearing whereby rod 156 may operate eccentric 152 to move the back 150 to and fro as the drag 3 travels. When drag 3 is at rest, hand lever 161 can be operated by a workman and the eccentric 152

thereby rocked and the movement of the back 150 to and from casting or matrix sheet supporting position may be effected, while the drag 3 is at rest, to fit the new 5 matrix sheet in position in the drag, or to preliminarily inspect its condition prior to casting, or for other purposes as may be convenient or desirable.

The invention in its broader aspects is 10 not limited to the specific mechanism shown and described but departures may be made therefrom within the scope of the accompanying claims without departing from the principles of the invention and without 15 sacrificing its chief advantages.

What I claim is:—

1. A machine for casting stereotype plates including in combination plate casting means including a drag movable to and fro between plate casting position and plate discharging position and means for lifting the plate free from the matrix and from the wall of the drag and bringing it to rest within the drag ready for removal. 20

2. A machine for casting stereotype plates including in combination plate casting means including a drag movable to and fro between plate casting position and plate discharging position and means operating 25 automatically for lifting the plate free from the matrix and from the wall of the drag and bringing it to rest within the drag ready for removal.

3. A machine for casting stereotype plates including in combination plate casting means including a drag movable to and fro between plate casting position and plate discharging position and means operated 30 automatically by the travel of the drag for lifting the plate free from the matrix and from the wall of the drag and bringing it to rest within the drag ready for removal.

4. A machine for casting stereotype plates including in combination plate casting 35 means including a drag movable to and fro between plate casting position and plate discharging position and means for engaging the plate at its curved ends to lift the plate free from the matrix and from the wall of the drag and bringing it to rest within the drag ready for removal.

5. A machine for casting stereotype plates including in combination plate casting means including a drag movable to and 40 fro between plate casting position and plate discharging position and means operating automatically for engaging the plate at its curved ends to lift the plate free from the matrix and from the wall of the drag and bringing it to rest within the drag ready for removal.

6. A machine for casting stereotype plates including in combination plate casting 45 means including a drag movable to and fro between plate casting position and plate

discharging position and means operated automatically by the travel of the drag for engaging the plate at its curved ends to lift the plate free from the matrix and from the wall of the drag and bringing it to rest within the drag ready for removal. 70

7. A machine for casting stereotype plates including in combination plate casting means including a drag movable to and fro between plate casting position and a substantially horizontal plate discharging 75 position, and means for lifting the plate free from the matrix and from the wall of the drag and bringing it to rest within the drag ready for removal.

8. A machine for casting stereotype plates including in combination plate casting means including a drag movable to and fro between plate casting position and a substantially horizontal plate discharging 80 position, and means operating automatically for lifting the plate free from the matrix and from the wall of the drag and bringing it to rest within the drag ready for removal.

9. A machine for casting stereotype plates including in combination plate casting means including a drag movable to and fro between plate casting position and a substantially horizontal plate discharging 85 position, and means operated automatically by the travel of the drag for lifting the plate free from the matrix and from the wall of the drag and bringing it to rest within the drag ready for removal. 90

10. A machine for casting stereotype plates including in combination plate casting means including a drag movable to and fro between plate casting position and a substantially horizontal plate discharging 100 position, and means for engaging the plate at its curved ends to lift the plate free from the matrix and from the wall of the drag and bringing it to rest within the drag ready for removal. 105

11. A machine for casting stereotype plates including in combination plate casting means including a drag movable to and fro between plate casting position and a substantially horizontal plate discharging 110 position, and means operating automatically for engaging the plate at its curved ends to lift the plate free from the matrix and from the wall of the drag and bringing it to rest within the drag ready for removal. 115

12. A machine for casting stereotype plates including in combination plate casting means including a drag movable to and fro between plate casting position and a substantially horizontal plate discharging 120 position, and means operated automatically by the travel of the drag for engaging the plate at its curved ends to lift the plate free from the matrix and from the wall of the drag and bringing it to rest within the drag ready for removal. 125

- the wall of the drag and moving outwardly therefrom and engaging the plate at its curved ends to lift the plate free from the matrix and from the wall of the drag and bringing it to rest within the drag ready for removal.
25. A machine for casting stereotype plates including in combination plate casting means including a drag movable to and fro between plate casting position and plate discharging position and means comprising arcuate saddles nested in the wall of the drag and moving outwardly therefrom to lift the plate free from the matrix and from the wall of the drag and bringing it to rest within the drag ready for removal.
26. A machine for casting stereotype plates including in combination plate casting means including a drag movable to and fro between plate casting position and plate discharging position and means operating automatically comprising arcuate saddles nested in the wall of the drag and moving outwardly therefrom to lift the plate free from the matrix and from the wall of the drag and bringing it to rest within the drag ready for removal.
27. A machine for casting stereotype plates including in combination plate casting means including a drag movable to and fro between plate casting position and plate discharging position and means operated automatically by the travel of the drag comprising arcuate saddles nested in the wall of the drag and moving outwardly therefrom to lift the plate free from the matrix and from the wall of the drag and bringing it to rest within the drag ready for removal.
28. A machine for casting stereotype printing plates comprising a drag having an arcuate plate saddle nested in the concave wall of the drag and engaging with the convex side of the plate, and means slidably engaging the drag for lifting the saddle.
29. A machine for casting stereotype printing plates comprising a drag having an arcuate plate saddle nested in the wall of the drag in position to engage the plate away from the printing portion and means for imparting rectilinear motion thereto to and from its nest.
30. A machine for casting stereotype printing plates comprising a drag having an arcuate plate saddle nested in the wall of the drag to engage with the convex face of the plate, and spring-pressed means for moving said saddle to the nested position.
31. A machine for casting stereotype printing plates comprising a drag having an arcuate plate saddle nested in the concave wall of the drag, means for imparting rectilinear motion thereto to and from its nest, and spring-pressed means impelling said saddle in one direction.
32. A machine for casting stereotype printing plates comprising a drag having an arcuate plate saddle nested in the concave wall of the drag, means for imparting rectilinear motion thereto to and from its nest, and spring-pressed means impelling said saddle into its nest.
33. A machine for casting stereotype printing plates comprising a drag having an arcuate plate saddle nested in the wall of the drag, and means operated by the travel of the drag for imparting rectilinear motion thereto to and from its nest.
34. A machine for casting stereotype printing plates comprising a drag having an arcuate plate saddle nested in the wall of the drag engaging the convex face of the plate, and means passing through the drag for imparting motion thereto to and from its nest.
35. A machine for casting stereotype printing plates comprising a drag having an arcuate plate saddle nested in the wall of the drag, and means operated by the travel of the drag for imparting motion thereto to and from its nest.
36. A machine for casting stereotype printing plates comprising a drag having an arcuate plate saddle nested in the concave wall of the drag, and spring-pressed means for moving said saddle, and means for moving the saddle in one direction against the spring-pressed means.
37. A machine for casting stereotype printing plates comprising a drag having an arcuate plate saddle nested in the concave wall of the drag and spring-pressed means impelling said saddle into its nest and means for moving the saddle out of its nest against the action of the spring-pressed means.
38. A machine for casting stereotype printing plates comprising a drag having a pair of plate saddles nested in the wall of the drag adjacent to each end of the plate, means for positioning a matrix between the drag and plate, and means for moving the saddles outwardly in a rectilinear path to lift the plate clear of the matrix and drag wall and to bring it to rest ready for delivery.
39. A machine for casting stereotype printing plates comprising a drag having a pair of plate saddles nested in the concave wall of the drag adjacent to each end of the plate and spring-means pressing the saddles into their nests and means for moving the saddles outwardly against the action of the spring-pressed means to lift the plate clear of the matrix and drag wall and to bring it to rest ready for delivery.
40. A machine for casting stereotype

printing plates comprising a drag having a pair of arcuate plate saddles nested in the concave wall of the drag adjacent to each end of the plate and means passing through the drag for moving the saddles outwardly to lift the plate clear of the matrix and drag wall and to bring it to rest ready for delivery.

41. A casting machine including in combination members constituting a curved casting chamber, one member having means for holding a matrix, said members forming a casting chamber for casting a plate with a tail at each curved end thereof.

42. A machine for casting stereotype plates comprising a drag movable to and fro between plate casting position and plate discharging position, and means, operated automatically by the travel of the drag, or operated manually, for lifting the plate free from the matrix and from the wall of the drag and bringing it to rest within the drag ready for removal.

43. A casting machine having a casting chamber comprising a drag and adapted to cast a hemi-cylindrical plate with a tail projecting from each curved end thereof and means for engaging the tails at each end of the plate to lift the plate from the drag.

44. A casting machine having a casting chamber comprising a drag and adapted to cast a hemi-cylindrical plate with a tail projecting from each curved end thereof and a pair of arcuate saddles for engaging the tails at each end of the plate to lift the plate in a straight line from the drag.

45. A casting machine having a casting chamber comprising a drag and adapted to cast a hemi-cylindrical plate with a tail projecting from each curved end thereof and means nested in the wall of the drag for engaging the tails at each end of the plate to lift the plate from the drag.

46. A casting machine having a casting chamber comprising a drag and adapted to cast a hemi-cylindrical plate with a tail projecting from each curved end thereof and a pair of arcuate saddles nested in the wall of the drag for engaging the tails at each end of the plate to lift the plate in a straight line from the drag.

47. A casting machine having a casting chamber comprising a drag and adapted to cast a hemi-cylindrical plate with a tail projecting from each curved end thereof and means for engaging the tails at each end of the plate to lift the plate from the drag and means automatically operating said plate lifting means.

48. A casting machine having a casting chamber comprising a drag and adapted to cast a hemi-cylindrical plate with a tail projecting from each curved end thereof and means for engaging the tails at each

end of the plate to lift the plate from the drag and means automatically operating by the movement of the drag to operate said plate lifting means.

49. In a stereotype plate casting machine an end ring for the matrix sheet and a plate lifting device moving together in a straight line in a substantially vertical direction.

50. In a stereotype plate casting machine a unitary end ring and plate lifting saddle, and means for imparting rectilinear motion in a substantially vertical direction to said ring and saddle.

51. A stereotype plate casting machine including in combination casting mechanism including a drag, a pair of unitary end rings and saddles at each end of the matrix and means passing through the drag for moving them together to deliver the plate.

52. A stereotype plate casting machine including in combination casting mechanism including a drag, and a pair of unitary end rings and saddles at each end of the matrix and means operating automatically upon the return of the drag from the casting position for moving them together to deliver the plate.

53. A machine for casting stereotype plates including in combination a drag, unitary end rings and plate saddles and means for lifting them to raise the cast plate from the drag.

54. A machine for casting stereotype plates including in combination a drag, matrix stripping devices, unitary end rings and plate saddles and means for lifting them to raise the cast plate from the drag and to permit the matrix stripping devices to strip the matrix from the plate as the unitary rings and saddles are raised.

55. A machine for casting stereotype plates including in combination a drag, unitary end rings and plate saddles and automatically operating means for lifting them to raise the cast plate from the drag.

56. A machine for casting stereotype plates including in combination a drag, unitary end rings and plate saddles and means operated by the movement of the drag for lifting them to raise the cast plate from the drag.

57. A machine for casting stereotype plates including in combination a drag, matrix - protecting end rings movable to lift the cast plate and means passing through the drag for lifting the rings.

58. A machine for casting stereotype plates including in combination a drag, matrix stripping means, end rings movable to lift the cast plate and means for lifting the rings to lift the plate and to permit the stripping of the matrix as the unitary rings and saddles are raised.

59. A machine for casting stereotype

plates including in combination a drag, end rings movable to lift the cast plate and automatically operating means for lifting the rings.

5 60. A machine for casting stereotype plates including in combination a drag, end rings movable to lift the cast plate and means operated automatically by the movement of the drag for lifting the rings.

10 61. A machine for casting stereotype plates including in combination a drag, matrix-protecting end rings movable to lift the cast plate and means passing through the drag and manually operated for lifting

15 the rings.

62. A machine for casting stereotype plates including in combination a drag, end rings movable to lift the cast plate and alternatively utilizable means for manually

20 and automatically lifting the rings.

63. A machine for casting stereotype plates including in combination a drag, end rings movable to lift the cast plate and alternatively utilizable means for manually

25 and automatically lifting the rings.

64. A machine for casting stereotype plates including in combination a drag, plate lifting saddles mounted in the drag to engage the convex side of the plate, and means passing through the drag for operating the saddles to lift the plate from the drag in a vertical rectilinear path.

65. A machine for casting stereotype plates including in combination a drag, plate lifting saddles, means for operating the saddles to lift the plate from the drag, and actuating means for the saddle lifting

means operated optionally by an attendant or automatically by the machine.

66. A machine for casting stereotype plates including in combination a drag, plate lifting saddles mounted in the drag to engage the convex side of the plate, and means passing through the drag actuated by an attendant for operating the saddles to lift the plate from the drag.

67. A machine for casting stereotype printing plates including in combination a drag movable to and fro between casting position and plate discharging position, and means slidably engaging the drag for lifting the plate in a substantially rectilinear path.

68. A machine for casting stereotype printing plates including in combination a drag movable to and fro between casting position and plate discharging position, means slidably engaging the drag for lifting the plate in a substantially rectilinear path, and means for holding the matrix while the plate is lifted from it.

69. A machine for casting stereotype printing plates including in combination a drag movable to and fro between casting position and plate discharging position, means passing through the drag for lifting the cast plate free from the matrix and bringing it to rest within the drag ready for removal, and means for holding the matrix while the plate is lifted from it.

In testimony whereof, I have signed my name to this specification.

MARTIN W. BRUESHABER.
